(57) **CLAIM**

The ornamental design for a portable firepit with a hexagonal configuration, as shown and described.

DESCRIPTION

FIG. 1 is a front view of a portable firepit with a hexagonal configuration, which is the subject of the present invention showing our new design;

FIG. 2 is a rear view of the portable firepit with a hexagonal configuration illustrated in FIG. 1;

FIG. 3 is a side view of the portable firepit with a hexagonal configuration illustrated in FIG. 1 and FIG. 2;

FIG. 4 is an opposite view of the portable firepit with a hexagonal configuration illustrated in FIG. 1, FIG. 2, and FIG. 3;

FIG. 5 is a plan top view of the portable firepit with a hexagonal configuration illustrated in FIG. 1, FIG. 2, FIG. 3 and FIG. 4;

FIG. 6 is a plan bottom view of the portable firepit with a hexagonal configuration illustrated in FIG. 1, FIG. 2, FIG. 3, FIG. 4 and FIG. 5;

FIG. 7 is an isometric front view of the portable firepit with a hexagonal configuration illustrated in FIG. 1, FIG. 2, FIG. 3, FIG. 4, FIG. 5 and FIG. 6 from a superior angle; and, FIG. 8 is an isometric front view of the portable firepit with a hexagonal configuration illustrated in FIG. 1, FIG. 2, FIG. 3, FIG. 4, FIG. 5 and FIG. 6 from an inferior angle.
